SYSTEM FOR SOUND RECORDING

Barton Kreuzer, Los Angeles, Calif., and Hillel I. Reiskind, Camden, N. J., assignors to Radio Corporation of America, a corporation of Delaware

Application April 2, 1940, Serial No. 327,436

16 Claims. (Cl. 179—100.3)

This invention relates to sound recording systems and particularly to such systems wherein the signal variations are impressed upon the film as a combination of variable area and variable intensity variations in a light beam or beams. These systems also embody noise reduction and compression.

Variable area sound recording systems, in which the sound tracks appear as opaque and transparent longitudinal areas separated by a varying trace or traces which correspond to the frequency and amplitude of the signal, are well known, as well as the variable density type of system wherein the variations in frequency and amplitude appear on the sound track as striations of constant width but of varying density. Noise reduction in the form of a longitudinal opaque section varying in width substantially in accordance with the average amplitude or envelope of the signal is well known for variable area systems, and in the form of variations in the average density of the film in accordance with the average or envelope amplitude of the signal, is well known for variable density systems.

In the present invention, the variable area and variable density components are combined in a manner to obtain the optimum signal-to-noise ratio, while the noise reduction action is particularly effective during the silent periods or times of no signal.

The invention may also embody the feature of overall compression which has been found to be advantageous in the recording of sound-on-film for reproduction in various theatres having different acoustic characteristics. The use of compression also aids the recording operators to produce a better overall sound track particularly when the amplitude range of the signal is much greater than the film range.

The present invention will thus produce a combination variable area-variable density sound track having noise reduction and compression, the advantages of each individual feature being retained in the process.

The principal object of the invention, therefore, is to improve and facilitate the recording of sound-on-film.

Another object of the invention is to obtain an improved sound track record.

A further object of the invention is to record sound having both variable area and variable density components with noise reduction.

A further object of the invention is to obtain a sound track combining both variable density

and variable area components with noise reduction and compression.

Another object of the invention is to record sound having both variable area and variable density components with at least one of said components being nonproportional to the amplitude variations in the original signal.

Another object of the invention is to produce a sound track having variable area and variable density components in which the combination of variable area and variable density components is not proportional to the variations in the original signal.

Although the novel features which are believed to be characteristic of this invention are pointed out with particularity in the claims appended herewith, the manner of its organization and the mode of its operation will be better understood by referring to the following description read in conjunction with the accompanying drawings forming a part thereof, in which—

Figure 1 is a diagrammatic drawing of one embodiment of the invention;

Figure 2 is a diagrammatic drawing of a second embodiment of the invention;

Figure 3 is a diagrammatic drawing of a third embodiment of the invention;

Figure 4 is a schematic circuit drawing of a portion of the embodiments shown in Figs. 1, 2 and 3;

Figure 5 is a partial view of the appearance of a sound track made with the recording systems embodying the invention; and

Figures 6, 7, 8, 9, 10 and 11 are graphs illustrating the operation of the systems of Figs. 1, 2 and 3.

Referring now to Fig. 1, a microphone 5 feeds a standard amplifier 6, the output of which is divided, one portion being impressed upon a noise reduction unit 7, another portion being impressed upon a compressor 8, and a third portion upon a monitor amplifier 9, to which is connected a loudspeaker 10. The output of the compressor is impressed upon a galvanometer 12 or other light modulating device, while the output of the noise reduction unit 7 is impressed upon a noise reduction shutter or shutters 14 or other type of noise reduction element. The output of noise reduction unit 7 may also be impressed upon the galvanometer 12.

In Fig. 2 another arrangement of the compressor 8 in the system of Fig. 1 is shown wherein the output of amplifier 6 feeds only the compressor 8 and the monitor amplifier 9 with its loudspeaker 10. In this modification, the out-

put of compressor 8 is impressed upon noise reduction unit 7 for feeding the shutter 14 and also upon the galvanometer 12.

In the embodiment of Fig. 3, the output of amplifier 6 is again divided into three portions, one portion feeding the monitor amplifier 9 with its loudspeaker 10, the second portion feeding the compressor 8, and the third portion feeding a second compressor 15, which feeds the regular noise reduction unit 7 and shutters 14. The output of compressor 8 is impressed upon the galvanometer 12 in the same manner as shown in Figs. 1 and 2. The details of the compressor shown at 8 and 15 in Figs. 1, 2 and 3 may be of any standard type, a preferred form being disclosed and claimed in copending application, Serial No. 263,884, filed March 24, 1939.

Referring now to Fig. 4, showing a schematic circuit of the noise reduction portion of the systems shown schematically in Figs. 1, 2 and 3, the microphone 5 and amplifier 6 feed the compressor unit 8, as shown in Fig. 1, through a booster amplifier 11 and manual control attenuator 13, the other portion of the output of amplifier 6 being impressed upon the noise reduction unit comprising a transformer 17 feeding a rectifier element 18 which is coupled to a direct current amplifier tube 19 through a filter-timing circuit including resistances 21 and 22 and condenser 23. The bias for the direct current amplifier 19 is obtained from a variable tap on a resistance 28 shunting a potential source such as a battery 29, while a threshold bias for the rectifier 18 is obtained from a potentiometer 20 shunting a potential source 24. The output of the amplifier 19 is shown connected through a potential source 31 and an operating coil 32 shunted by a condenser 33 for controlling the separation of a pair of shutters 34. The condenser 33 may or may not be employed, depending upon the natural time constant of the shutter circuit. Connected in dotted lines across the winding 32 is a coil 62 for actuating a penumbra noise reduction shutter 63, as will be explained hereinafter. Such a penumbra sound recording system is disclosed and claimed in copending application Serial No. 265,278, filed March 31, 1939. Although the penumbra coil 62 is shown being operated from the same noise reduction unit feeding the shutter coil 32, the penumbra coil may be separately actuated from a second noise reduction unit operating in parallel with the one shown.

The shutters 34 are of the noise reduction type employed in the standard variable area sound recording system. The present system uses these shutters for obtaining the variable area component of the sound track in association with a light source 35, a condenser lens 36, and a mask 37 with a rectangular aperture 38 therein. The light permitted to pass through the aperture 38 is projected upon a mirror 40 of the galvanometer 12 by a lens 41 after passing a fixed penumbra stop 64 and the variable penumbra shutter 63, from whence it is reflected to a slit mask 42 having a narrow elongated slit 43 therein. The light beam appearing on the mask 42 is shown as a rectangular beam graduating in intensity in a direction normal to the slit 43. The light passing the slit 43 is projected upon a sound track portion 45 of a film 46 by projection lenses 47. The galvanometer mirror 40 is actuated by a coil 49 fed from the compressor 8. The noise reduction unit shown schematically in Fig. 4 may correspond to block 7 in Figs. 1, 2 and 3, while the shutter 34 may be the shutter block 14, and the

mirror 40 and coil 49 comprise the galvanometer 12 of these figures.

Although the effect of noise reduction is to reduce the light passing to the photocell at low modulations, it has also been found desirable in noise reduction to permit a small amount of light to pass to the photoelectric cell during the silent portions of the film to prevent so-called "breathing" during reproduction and to insure the recording of the low modulations. Although there are many salient features provided by compression in sound recording, it could be repeated that compression is desirable from the standpoint of aiding the sound recording operators to obtain an intelligible recording of high momentary signal peaks which otherwise would be beyond the range of the film, and to obtain better overall intelligibility when the sound tracks are reproduced in theatres having poor acoustic characteristics.

By now referring to the various graphs, the operation of the recording systems shown in Figs. 1, 2 and 3 will be explained. In all these graphs, the dotted lines represent the relationship between the input level or amplitude range of the signal and the reproduced level in db. for the variable density component. The solid line represents the same relationship with respect to the variable area component. The dash-and-single-dot line shown at 45° in Figs. 6, 7, 8 and 9 represents the overall relationship between input level and reproduced level of the signal, while this line has been placed in Figs. 10 and 11 for purposes of comparison. It will be noted that, in accordance with Fig. 4, the variable area component is produced by the noise reduction shutters 34 varying the dimensions of the light beam, while the variable density component is produced by the vibrations of the mirror 40 passing varying light densities through the slit 43, variable density noise reduction being simultaneously obtainable by operation of the penumbra shutter 63 if desired either by the same noise reduction unit or by a separate one.

Now, referring to Fig. 6, in which full-track modulation is taken as zero db. and equal to zero db. input level, it will be found that the noise reduction shutters 34 or variable area component follows the envelope of the amplitudes of the input signal in a linear relationship to an input level of minus 40 db., while this range of input levels has been compressed into approximately .1 db. of reproduced output for the variable density component. In other words, the variable density component is substantially 100% modulated over the minus 40 to zero input range providing a high signal to noise ratio. The result of the two components over this important range of input levels is substantially linear, the amplitude of the variable density component remaining almost constant, while the amplitude of the area component controls output volume. At minus 40 db., however, the noise reduction shutters 34 do not respond to further decreases in input level due to the bias placed on the rectifier 18 by potentiometer 20 or by mechanically blocking the shutters 34 at a minimum position, while the variable density component becomes linear or proportional with respect to the variations in input level. This condition obtains to an input level of approximately minus 80 db., which is probably below the lowest level sounds which are suitable for recording, as the ground noise level is generally greater than this signal level. At the minus 40 db. reproduced level, the noise reduc-

tion shutters are brought together so that the width of the film zero line or variable area component is approximately 0.7 of a mil in width, which is sufficiently narrow to obtain optimum noise reduction. This 0.7 of a mil width is based upon a total track width of 70 or 76 mils. It is to be remembered that input levels in the range between minus 80 db. and minus 40 db. are comparatively unimportant with respect to the minus 40 to zero db. range. Thus, over the minus 80 to minus 40 db. range and at times of no signal, the optimum degree of variable area noise reduction is applied, while the low signal levels of minus 80 db. are expanded to correspond to an output level of minus 40 db., and thus provide a high signal to noise ratio for the density component at these low levels. Furthermore, with the variable density noise reduction elements 62 and 63 simultaneously operating, the density of the modulated portion as well as the unmodulated portion is increased in the print to further reduce the ground noise in accordance with well-known practice.

The resulting track is of the form illustrated in Fig. 5, although the film from a system operating as shown in Fig. 6 will not have the addition of the narrow traces 51 and 51' shown at both ends of a modulated portion of the film, but will have the constant area and variable density modulated portions 52 and 52' of a width comparable to traces 51 and 51', as will be explained. Fig. 5 is thus employed to illustrate the form of track producible by the different arrangements shown in Figs. 1, 2 and 3 as a simple signal is impressed upon the recording systems. It is difficult to show in a drawing the variations in the density component of the track, although it is to be noted by referring to Fig. 6 that the density modulation range between the points 55 and 56 and points 55' and 56' represents an input level range of between minus 40 and minus 80 db., which corresponds to a reproduced range of from minus 40 to zero db. In this range of minus 40 to minus 80 db. input levels, the width of the sound track remains constant, while the variable density modulations are directly proportional to the variations in input signal. It is also to be noted that, since the compressor circuit only feeds the galvanometer, the booster amplifier 11 and attenuator 13 (see Fig. 4) may be adjusted so that the low level range from minus 80 db. to minus 40 db. is amplified to a reproduced level of minus 40 db. to substantially zero db. before the nonlinear relationship obtains. This feature permits the obtaining of a high signal-to-noise ratio at the low signal amplitudes for the variable density component, while utilizing the intrinsic qualities of variable density recording. Furthermore, by connecting the dotted elements 62 and 63 into the circuit of Fig. 4, variable density noise reduction may be simultaneously applied as disclosed in the above-mentioned copending application Serial No. 265,278. If the density noise reduction elements are actuated by a separate noise reduction unit, the variable density noise reduction action may be applied only at the lower input levels. Also, variable density noise reduction may be applied by applying the output of tube 19 to a bias winding on the galvanometer, as disclosed and claimed in copending application Serial No. 311,638, filed December 29, 1939.

Thus, as the signal comes onto the recording system, the variable area component remains constant over the minus 80 db. to minus 40 db. range, while the variable density component is

raised approximately 40 db. in level to obtain substantially 100% variable density modulation at the minus 40 db. level and a high signal-to-noise ratio at all amplitudes. From the range of minus 40 db. to zero db. of input level, the variable density component remains substantially constant at 100% modulation, and the track varies only as to its area component, and that in a linear manner. It is to be noted that the variable area modulated portion 53 (see Fig. 5) between points 55 and 55' is shorter between point 55 and point 57 than between point 57 and lower point 55'. This is produced by the timing action of the elements 21, 22 and 23 in the output circuit of rectifier 18 (see Fig. 4). Thus, in the system just described, the advantages of variable density and variable area recording are combined along with the advantages of noise reduction. Although the area and density components have a certain relationship in Fig. 6, it is to be understood that this relationship may be reversed. Also, the particular values of input signal and output levels given are illustrative of a preferred form of variation and other ratios of compression as well as other ranges of levels are within the scope of the invention.

Referring now to Fig. 7, the same general type of operation is illustrated, but one which will be produced by the arrangement of the compressor and noise reduction units as shown in Fig. 2. In this case, the compressor operates both the variable density and variable area components. Specifically, an input level range between zero and minus 40 db. is compressed into a reproduced level range of between zero and minus 20 db. for both components, and the addition of both these reproduced levels will produce an output which will be proportional to the input variations in amplitude. It will be noted in the operation of Fig. 2 that, at minus 40 db., the variable area component becomes constant, which corresponds to the section between the points 55 and 56 in Fig. 5. Also, at the point of minus 40 db. input level in Fig. 7, the variable density component becomes linear so that the reproduced output is proportional to the recorded input below this level. By adjustment of the noise reduction circuit, the variable area component becomes constant at a minus 20 db. output level, which corresponds to approximately a 7 mil width of track. In Fig. 6, the operation is such that the area component is reduced to minus 40 db. or a 0.7 mil width. As the 0.7 mil width is preferred for periods of no signal, the area component may be reduced to this width by use of the noise reduction circuit shown in copending application Serial No. 270,876, filed April 29, 1939, in which bucking voltages are produced at predetermined signal levels. Such a circuit will provide a rapid action for low level signals so that as the input signal approaches minus 80 db., the shutters 34 (or penumbra shutter 63) will quickly come together to reduce the track to the .7 mil width, as shown in Fig. 7. By use of the parallel arrangement of rectifiers, the shutters will be held fixed over a predetermined range of levels, while the shutters may be given minimum position of separation by a separation block placed therebetween. Thus, as in Fig. 6, the variable area component is reduced to the desired optimum width in the neighborhood of minus 80 db. This no-signal condition is illustrated in Fig. 5 by zero lines 51 and 51', while in Fig. 6, the constant area variable density modulated region would be of comparable width to lines 51

and 51'. It will be noted in Fig. 7 that the variable density component of minus 80 db. corresponds to a reproduced level in the neighborhood of minus 60 db. so the booster amplifier 11 and attenuator 13 will be adjusted differently to produce the results shown in Figs. 6 and 7.

Referring now to Fig. 8, this graph represents the operation of the arrangement shown in Fig. 3, wherein a different compression rate is applied to the variable density component than to the variable area component, the combination of both, however, producing a linear relationship between the input level and the reproduced level. In this system, a range of zero to minus 40 db. is compressed into a range of zero to minus 10 db. for the variable density component, while the variable area component is the reciprocal thereof and has an input range of zero to minus 40 db. compressed into a reproduced range of zero to minus 30 db. At minus 40 db. input level, the variable area component remains constant, while the variable density component becomes linear with respect to input level, while in the neighborhood of minus 80 db. the area component is reduced to a .7 mil width to reduce ground noise at no-signal periods in the same manner as in Fig. 7. Also, the attenuator is adjusted to boost the minus 80 db. input level to a minus 50 db. output level providing a high signal-to-noise ratio for low amplitude signals.

Referring now to Fig. 9, another modification of the operation of the system of Fig. 3 is shown, wherein the variable area component of the sound track has an input level range of zero to minus 40 db. compressed into a range of zero to minus 10 db. output level, while the variable density component has a range of zero to minus 40 db. compressed into an output range of zero to minus 30 db. At minus 40 db. input level, the variable area component remains constant, while the variable density component varies linearly between the input and output levels. In this figure, it is also to be noted that the variable area component is reduced to the .7 mil width in the neighborhood of minus 80 db. input level. By the use of two compressors, it is obvious that any desired combination of compression ratios is obtainable.

In the operation of the systems shown in Figs. 1, 2 and 3 and illustrated in the graphs of Figs. 6, 7, 8 and 9, the overall relationship between signal input level and output or reproduced level is strictly linear or proportional even though compression is used for one or both components. These variable compression rates and variable break-away points are easily obtainable with the circuit disclosed and claimed in the above-mentioned copending application, Serial No. 263,884. Now, in Figs. 10 and 11, it is shown wherein the systems of Figs. 1, 2 and 3 may be operated to obtain an overall compression. In other words, compression or expansion may be added to a sound track having the advantages of variable area and variable density recording with noise reduction.

Referring now to Fig. 10, it will be noted that the variable density component has a linear compression over a range of zero to minus 80 db. input level which corresponds to a range of zero to minus 40 db. reproduced level. A similar compression exists for the variable area component, but the compression rate varies over this range such that a range of minus 35 db. to zero input level is compressed into a 10 db. range

of output level, while the range of minus 35 db. to minus 70 db. input level is compressed into 20 db. of output level. Thus, the overall relationship between the input signal and a reproduced level will correspond to the dash-and-double-dot line shown in this figure.

Fig. 11 is a graph representing the operation of a system providing the same overall results of Fig. 10 except that the variable area and variable density compressors are reversed in their operation. It will be noted that in both Figs. 10 and 11, the no-signal noise reduction action of the variable area component is present to reduce the width of the track to .7 mil during the no-signal periods. Although a compression action has been shown in Figs. 10 and 11, it is to be understood that expansion is readily obtainable by reversing the action of the compressor. Although Figs. 10 and 11 show results obtainable with the circuit arrangement of Fig. 3, overall compression and expansion are also obtainable with the arrangements of Figs. 1 and 2. Furthermore, the compression ratio curves may be of any desired shape, such as both constant, both variable, or one constant and the other variable as shown in Figs. 10 and 11.

Thus, with the above invention, the original input signal may be varied to enable a larger range to be recorded in the sound track area while obtaining the advantages of variable density and variable area recording, noise reduction and compression. It has been found that various types of signals are more suited to one or the other form of recording so that now the recorder operator may adjust his apparatus to choose the best recording conditions for a certain type of signal after he has determined its type during rehearsal or otherwise.

We claim as our invention:

40. 1. A sound recording system comprising a signal source, a light source, means for modulating the intensity of the light from said source in accordance with the instantaneous amplitudes of the signal from said source, means for modulating said light in accordance with the average value of the amplitudes of said signal, and means for varying the rates of modulation of said light by said respective means in accordance with the range of amplitudes being recorded, said average value modulating means remaining ineffective over a certain portion of said range of amplitudes.

53. 2. A sound recording system in accordance with claim 1 which includes means for defining said light into a beam, said average value modulating means varying the size of said beam, and means for maintaining said average value modulating means substantially unresponsive to changes in the average value of the amplitudes of said signal over a predetermined amplitude range of said signal.

55. 3. A sound recording system in accordance with claim 1 which includes means for defining said light into a beam, said average value modulating means varying the size of said beam, and means for maintaining said average value modulating means substantially unresponsive to changes in the average value of the amplitudes of said signal over a predetermined amplitude range of said signal, and responsive to the average value of said amplitudes of said signal above said predetermined range at one rate and responsive at a different rate to said signal amplitude below said predetermined range.

60. 4. A sound recording system comprising a

source of sound waves, a source of light waves, means for forming said light waves into a definite shaped beam, means for varying the shape of said beam by said sound waves, means for varying the intensity of said light waves in said beam by said sound waves, means included in said shape varying means for varying the shape of said beam differently over selective ranges of amplitudes of said sound waves, and means included in said intensity varying means for varying the intensity of said beam differently over selective ranges of amplitudes of said sound waves.

5. A sound recording system in accordance with claim 4 in which the combination effect of the variations of shape of said beam and the variation in intensity of said beam over any definite amplitude range is proportional to the instantaneous variations in amplitude of said sound waves.

6. A sound recording system in accordance with claim 4 in which said means included in said intensity varying means is a compressor of the instantaneous amplitudes of said sound waves effective over a predetermined range of said sound waves.

7. A sound film record having a variable area modulation component and a variable density modulation component, the combination of said components being substantially proportional to sound waves being recorded, said record embodying noise reduction in the form of a narrow constant area region having a relatively high opacity during times of no signal and low amplitude modulations.

8. A sound film record having a variable area modulation component over a predetermined width of said record, and a constant area over another predetermined width of said record, a variable density modulation component over a predetermined width of said record, and a substantially constant variable density modulation over another predetermined width of said record.

9. A sound film record in accordance with claim 8 in which said record has a substantially constant average density over the portion thereof of having said variable density modulation.

10. The method of sound recording comprising translating sound waves into electrical currents, varying the intensity of a light beam in accordance with the instantaneous values of said currents, varying the dimensions of said light beam in accordance with the average value over only certain amplitudes of said currents while maintaining said dimensions constant over other amplitudes of said currents, and varying the average intensity of said light beam in accordance with the average value of said currents.

11. The method of sound recording comprising translating sound waves into electrical currents, modulating the intensity of a light beam in accordance with the instantaneous amplitudes of

said currents in direct ratio to the variations in said amplitudes over a portion of the range of said amplitudes and in a variable ratio over another range of said amplitudes, and modulating the area of said light beam in accordance with the average value of said currents in an inverse ratio to the ratio of variations in the intensity modulation of said light beam.

12. A sound recording system comprising a source of sound waves, means for producing a light beam, means for varying the intensity of said light beam in accordance with the instantaneous values of said sound waves, said means including means for amplifying and compressing currents representing a predetermined range of amplitudes of said sound waves, means for modulating said light beam in accordance with the average values of the amplitudes of said sound waves, said means including means for rectifying and amplifying currents produced by said sound waves, and means for varying the dimensions of said light beam, said last-mentioned means varying the dimensions of said light beam in inverse ratio to the variations produced by said intensity varying means, said dimension varying means being substantially inactive over a predetermined range of amplitudes of said sound waves.

13. A sound recording system in accordance with claim 12 in which said means for modulating said light beam in accordance with the average values of the amplitudes of said sound waves includes means for varying the average intensity of said light beam in accordance with the average amplitude values of said sound waves.

14. A sound film record having a variable area modulation component over a predetermined range of recorded sound waves, and a constant area over another range of recorded sound waves, a variable density modulation component over both of said ranges of recorded sound waves, said density component being directly proportional to said sound waves over the range of sound waves recorded when said record has a constant area.

15. A sound film record in accordance with claim 14 in which the average density of said record over said constant area increases as the recorded sound waves decrease in amplitude.

16. A sound recording system comprising a source of sound waves, means for forming light into a beam, means for varying the dimensions of said beam in accordance with the average values of the amplitudes of said sound waves, means for varying the intensity of said beam in accordance with the instantaneous values of said sound waves, and means for reducing the dimensions of said beam to a predetermined minimum during times of no sound waves and during times said sound waves have low amplitudes.
